UNITED STATES PATENT OFFICE.

FRANKLIN F. BRADLEY, OF CHICAGO, ILLINOIS, ASSIGNOR TO BRADLEY AND VROOMAN COMPANY, OF CHICAGO, ILLINOIS, A CORPORATION OF ILLINOIS.

PROCESS OF COATING OBJECTS WITH SUBDIVIDED MATERIAL.

997,436.

Specification of Letters Patent. Patented July 11, 1911.

Application filed March 13, 1911. Serial No. 614,001.

To all whom it may concern:

Be it known that I, FRANKLIN F. BRADLEY, citizen of the United States, residing at Chicago, in the county of Cook and State of Illinois, have invented a certain new and useful Improvement in Processes of Coating Objects with Subdivided Material, of which the following is a full, clear, concise, and exact description, reference being had to the accompanying drawings, forming a part of this specification.

My invention relates to a process of coating objects with subdivided material and is of particular service in the coating of objects with bronze powder, though the process is not to be limited to this use.

The invention has for one of its purposes the provision of a process whereby various parts of objects having a multiplicity of surfaces may be coated, and the invention has for another purpose the provision of a process whereby the subdivided material is so applied as to impart a superior finish to the objects coated therewith with a minimum quantity of subdivided material, though the invention is not to be limited to the achievement of both purposes.

In practicing the process of my invention I coat a multiplicity of surfaces of the object with some suitable adhesive material such as a wet varnish, though I do not limit myself to the nature of the adhesive material employed. I further employ a gaseous body which is substantially confined and is adapted to have a floating action upon the particles of subdivided material so that these particles may move with a light irregular course. The object with the wet varnish or other adhesive material thereupon is placed within the gaseous body in which the particles of subdivided material substantially float, the object being so placed as to be substantially surrounded by the gaseous body in substantially all planes in order that the particles may float toward the various surfaces of the object and be deposited thereupon. It is not necessary to employ a gaseous body that will hold the particles of subdivided material permanently in suspension, as a gaseous body which will permit the particles to settle after the lapse of a considerable period of time may be employed providing such gaseous body exerts floating action upon the particles sufficiently long to enable said particles to be deposited upon

the object. In the case of bronze powder, a body of air will exert the required floating action upon the bronze particles. I force the movement of the air so that the bronze particles will be moved toward the object to be coated. The pressure exerted upon the air in order to effect this movement is desirably very low, say three ounces per square inch. By causing the bronze powder to float in the moving air, it is prevented from having abrasive action upon the object to be coated therewith, a result which is highly important. In accordance with a specific feature of my present invention, to which specific feature, however, I do not wish to be limited, I cause the object to be coated to move within the gaseous body while enveloped thereby so that the various sides and surfaces of the object to be coated may be disposed at various angles with respect to the direction of movement of the gaseous body. In the preferred embodiment of the invention the object is rotated about a vertical axis of rotation while the general movement of the gaseous body is horizontal. Where the subdivided material is of a flaky formation, which is the case with bronze powder, I desirably apply a wet layer of adhesive material upon the object to be coated and which material is of such a nature that it is thereafter capable of being hardened, and has the property of disposing and, in hardening, of retaining the flakes substantially flat upon the surface of the applied adhesive material. By this operation I am enabled to apply to the object a smooth coating that is apparently homogeneous and which has the appearance either of a smooth sheet made of material from which the subdivided material is produced and which coating of subdivided material in fact might make it appear that the entire object possessing such a coating is of a nature throughout that is similar to such coating. Moreover I am enabled to use a minimum quantity of subdivided material in coating objects by employing the feature of my invention just described.

I believe the employment of adhesive material that will cause the flakes to dispose themselves in the manner which has been described is broadly new with me and I do not wish to be limited to the envelopment of the object to be coated by a body of gas for the purpose of depositing the flakes upon the object to be coated.

I will explain my invention more fully by reference to the accompanying drawings in which—

Figure 1 is an elevation, partially in section, of one form of the machine that may be employed in practicing the process of my invention; Fig. 2 is a vertical section on line 2 2 of Fig. 1; Fig. 3 is a sectional plan view on line 3 3 of Fig. 1; Fig. 4 shows a portion 10 of iron tubing that so commonly enters in the manufacture of Vernis Martin beds, this figure being intended to show the smooth nature of the metal coating with which the tubing is provided in accordance with one 15 feature of my invention; Fig. 5 is a view of a segment of the tubing shown in Fig. 4 but drawn on a much exaggerated scale; Fig. 6 is a longitudinal section of a portion of the tubing taken on a much exaggerated 20 scale; Fig. 7 is a face view of a portion of the outer surface of the tubing shown in Fig. 1, the flakes here being distinguished from each other by edge portions thereof, an appearance which is not, however, present 25 in the actual product as it is preferably produced, so far as the naked eye at least is concerned, the flakes in Fig. 7 being also shown on a much exaggerated scale; Fig. 8 is a view illustrating a very thin sheet of 30 bronze metal; and Fig. 9 illustrates a number of flakes of very small dimensions (the flakes being shown on an exaggerated scale) which are formed by grinding the sheet shown in Fig. 8.

Like parts are indicated by similar characters of reference throughout the different figures.

Referring first more particularly to Figs. 1 to 3 inclusive, I employ a receptacle *a* 40 into and out of which objects, such as metal bedstead parts, are moved upon a truck *b* through a doorway closed by a door *c*, a bedstead part *d* being indicated within the receptacle. A section *e* of suitable piping 45 leads from the air entrance side of the receptacle to a power-driven fan or blower *f*, the complementary section *g* of the piping leading from the blower to the air exit side of the receptacle located opposite the air 50 entrance side. The receptacle and piping substantially confine a body of air. The air is admitted into the receptacle through an elongated opening *h* in the right hand receptacle wall, this opening *h* presenting an 55 area that is substantially equal to the area of a right cross section of the pipe *e*, whereby the air is delivered into the receptacle in a flat stream at the place of entry and which stream is substantially the height of 60 the receptacle interior, whereby the air which substantially surrounds the object to be coated in substantially all planes moves throughout the height of the object. Some and preferably substantially the most of the 65 confined air is caused to flow by the object.

When the door *c* is shut, a body of air is enclosed by the receptacle and piping. The powdered or subdivided material, such as bronze powder, is admitted to the piping, preferably through an upright conduit *i*. 70 The powder is distributed by the fan throughout the flowing column of air in the piping and is conveyed by the moving air in which it floats to and through the interior of the receptacle. The truck *b* is carried by 75 a table *h'* upon which the truck may readily be rolled, blocks *i'* serving to hold the truck in position upon the table. The table is constituted a turn table by being mounted upon the upper end of the vertically disposed 80 shaft *k* that may be driven by any suitable driving mechanism such as that illustrated, which includes bevel pinions *l*, shafts *m* and a hand crank *o*.

By the mechanism illustrated, all parts to be coated of the object *d* may be properly presented to the stream of air carrying the subdivided material by rotating or swinging said object, and as the selected surfaces of the object have previously been provided with suitable adhesive material such as wet varnish, the lightly floating particles of bronze powder or other subdivided material that contact with the adhesive material are retained thereby and find lodgment without the aid of that forceful impact which would produce an abrasive action. By turning the object that is to be coated, the surfaces thereof that are to be coated are presented to the particles of subdivided material that are floating toward the object whereby the coating process is speeded. I prefer to rotate the object that is to be coated as I thereby present the various surfaces of the object to the advancing particles at a multiplicity of angles with respect to the general direction in which the air is being moved whereby the coating operation is not only performed but is performed very speedily. I do not limit myself in all claims to movement of the object during the coating process.

Referring now more particularly to Figs. 4 to 9 inclusive, each part *p* is provided on its outer surface with a wet layer of sizing *q* 115 which is capable of being hardened after it has been applied and which has the property of disposing and, in hardening, of retaining the metal flakes *r* substantially flat upon the surface of the applied adhesive material to which the metal flakes are applied, said adhesive material thereafter being allowed to harden to hold the metal flakes in the same general plane or curvature parallel with the surface of the part *p*. The metal flakes are capable of substantially 120 maintaining their own shape whereby the layer *q* of sizing is adapted to operate thereupon to dispose and hold the same in the manner which has been described. In Figs. 125 130

5 and 6 the flakes are, some of them, shown as being overlapped in shingle fashion. The very nature of the flakes prevents an accurate illustration of their appearance when 5 overlapping each other, the illustration in this regard being somewhat exaggerated in Figs. 5 and 6. The sizing or adhesive material with which excellent results may be secured and which is adapted to dispose and 10 hold the metal flakes in the manner which has been described has approximately 30 per cent. of its bulk made up of kauri, 5 per cent. of China wood oil (the oil of the nut of the tung tree), a fraction of a per cent., 15 or something in the nature of a trace, of a mixture of litharge and manganese dioxid, and the balance of the bulk of turpentine. After the object has been coated in the manner described it is preferably withdrawn 20 from the receptacle so that another object may be inserted in its place, it being permissible to allow the adhesive material to harden outside the receptacle.

I believe that I have been the first to coat 25 various surfaces of objects by enveloping the objects in the manner described and to which adhesive material has been applied in a gaseous body which has floating action upon particles of subdivided material with 30 which the objects are to be coated.

By means of the process of my invention the speed with which objects having a multiplicity of surfaces may be coated is greatly increased. Prior to my conception of the 35 method or process herein disclosed, the coating of ten metal beds with bronze by hand was considered to be a proper day's work for an ordinarily skilled workman. When the new process is employed the output per man 40 may be greatly increased, at least ten times as much work per man being possible. Moreover the results secured by means of my process are far more uniform and satisfactory.

45 I have disclosed apparatus for coating objects with subdivided material in my applications Serial No. 543,215, filed February 11, 1910; Serial No. 550,115, filed March 18, 1910; Serial No. 569,428, filed June 29, 1910; 50 Serial No. 588,730, filed October 24, 1910; Serial No. 588,731, filed October 24, 1910; Serial No. 603,251, filed January 18, 1911; Serial No. 603,726, filed January 20, 1911; Serial No. 609,203, filed February 17, 1911; 55 and Serial No. 611,042, filed February 27, 1911.

While I have shown one type of apparatus that may be used in practicing the process of my invention, I do not wish to be limited thereto.

Having thus described my invention, I claim as new and desire to secure by Letters Patent the following:

60 1. The process of coating objects having a multiplicity of surfaces with subdivided

material in the form of flakes which consists in placing a wet layer of adhesive material upon a multiplicity of surfaces of the object to be coated and which adhesive material is thereafter capable of being hardened, and has the property of disposing and, in hardening, of retaining the flakes of subdivided material substantially flat upon the surface of the applied adhesive material to which the flakes are applied; substantially confining a body of gas in which the subdivided material is adapted to float; distributing the subdivided material with which the object is to be coated in the body of gas, substantially surrounding the object in substantially all planes by the body of gas, and causing some of the gas in which subdivided material is floating to flow by the object, whereby various parts of the object having adhesive material thereon are coated with flakes of subdivided material.

65 2. The process of coating objects having a multiplicity of surfaces with subdivided material in the form of flakes which consists in placing a wet layer of adhesive material upon a multiplicity of surfaces of the object to be coated and which adhesive material is thereafter capable of being hardened, and has the property of disposing and, in hardening, of retaining the flakes of subdivided material substantially flat upon the surface of the applied adhesive material to which the flakes are applied; substantially confining a body of gas in which the subdivided material is adapted to float; distributing the subdivided material with which the object is to be coated in the body of gas; substantially surrounding the object in substantially all planes by the body of gas, causing some of the gas in which subdivided material is floating to flow by the object and causing the object to move, whereby various parts of the object having adhesive material thereon are coated with flakes of subdivided material.

70 3. The process of coating objects having a multiplicity of surfaces with subdivided material which consists in placing adhesive material upon a multiplicity of surfaces of the object to be coated; substantially confining a body of gas in which the subdivided material is adapted to float; distributing the subdivided material with which the object is to be coated in the body of gas; substantially surrounding the object in substantially all planes by the body of gas, and causing some of the gas in which subdivided material is floating to flow by the object, whereby various parts of the object having adhesive material thereon are coated with the subdivided material.

75 4. The process of coating objects having a multiplicity of surfaces with subdivided material which consists in placing adhesive material upon a multiplicity of surfaces of

the object to be coated; substantially confining a body of gas in which the subdivided material is adapted to float; distributing the subdivided material with which the object 5 is to be coated in the body of the gas; substantially surrounding the object in substantially all planes by the body of gas; causing some of the gas in which subdivided material is floating to flow by the object and 10 moving the object whereby various parts of the object having adhesive material thereon are coated with the subdivided material.

5. The process of coating objects with flakes of subdivided material which consists 15 in applying a wet layer of adhesive material upon a surface of the object to be coated

and which adhesive material is thereafter capable of being hardened, and has the property of disposing and, in hardening, of retaining flakes of subdivided material substantially flat upon the surface of the applied adhesive material to which the flakes are applied; disposing the flakes upon said adhesive material; and thereafter allowing the adhesive material to harden. 20 25

In witness whereof, I hereunto subscribe my name this 10th day of March A. D., 1911.

FRANKLIN F. BRADLEY.
